UNITED STATES PATENT OFFICE.

FRANK REESE, OF MINNEAPOLIS, MINNESOTA, ASSIGNOR TO REESE METAL WEATHER STRIP CO., OF MINNEAPOLIS, MINNESOTA, A CORPORATION OF MINNESOTA.

WEATHER STRIP.

Application filed September 14, 1925. Serial No. 56,157.

My present invention is directed to the provision of an improved weather strip for sliding window sashes, combining a flexible and adjustable weather strip with a channel-shaped metal parting strip. It is well known that the wood in sashes warps, swells and shrinks. My weather strip is so designed that it accommodates itself to the changing conditions of the sashes without loss of efficiency in preventing passage of air between the sashes and window frame. It is also well known that the usual wooden parting stops, or combinations of wood and metal parting stops, become loose in the frame, permitting leakage of air between the stop and the frame. The wooden parting stops are subject to decay, and are often broken or splintered. Practically all metal weather strips on the market today for sliding window sashes are attached to or fitted against the usual wooden parting stop, or some variation of the wooden parting stop, and such weather strips retain the weakness and comparatively short life of the wood stop.

My present invention is designed to entirely eliminate the wooden stop and provide a weather strip of the highest efficiency, adjustable to changing conditions of the sashes to which it is applied, and of greater durability than the wooden sashes and frame. Generally stated, the invention consists of the novel devices, combinations of devices and arrangement of parts hereinafter described and defined in the claims.

The invention is shown as applied to a vertically movable sash mounted to slide in the customary way in a wooden frame of standard or well known construction.

In the accompanying drawings, which illustrate the invention, like characters indicate like parts throughout the several views.

Referring to the drawings:

Fig. 1 is a fragmentary horizontal section showing portions of the window frame and sashes;

Fig. 2 is a fragmentary perspective of the parting strip shown in Fig. 1;

Fig. 3 is a fragmentary perspective of one of the weather strips shown in Fig. 1;

Fig. 4 is a diagrammatic view in elevation, showing the extent to which the weather

strips of the upper and lower sashes overlap when the upper sash is raised and the lower sash is lowered to closed positions;

Fig. 5 is a fragmentary horizontal section illustrating a modified construction and application of the weather strip and associated channel;

Fig. 6 is a fragmentary perspective of the channel shown in Fig. 5; and

Fig. 7 is a fragmentary perspective of the weather strip shown in Fig. 5.

Referring first to the construction illustrated in Figs. 1, 2, 3 and 4, the numeral 8 indicates a window frame having the customary outside stop plate 8^a and inside stop

strip 9, which latter, as is customary, is made readily removable by means of screws or nails. The upper and outer sash is indicated by the numeral 10 and the lower and inner sash by the numeral 10^a.

In the application of my invention, the parting strip, sometimes called the central stop strip, of the window frame structure is in the form of a metallic channel bar 11 preferably bent from sheet metal and having parallel sides.

This metallic parting strip is set into a groove formed in the main plate of the window frame and is detachably anchored thereto, preferably by screws 12. This parting strip will preferably be run from the top to the bottom of the window frame and, of course, there will be one on each side of the window frame. The weather strips, which are applied to the sashes, are also preferably made of sheet metal and they are bent to form laterally projecting anchoring flanges 13 and substantially rectangular folds 14.

These folds 14 are thus provided with parallel flat portions 14^a and 14^b, between which the co-operating flanges of the parting strip 11 are engaged with sufficient friction to insure very tight joints. The anchoring flanges 13 are attached to the respective sashes by nails or screws 15, so that the rectangular folds 14 lie very close to the opposing faces of the two sashes. The weather strips just described are preferably made the full length of the respective sashes,

so that they will overlap, substantially as indicated in Fig. 4, when the upper sash is raised and the lower sash is lowered to extreme closed positions. This maintains the

80

100

rectangular folds of the two weather strips always in overlapped relation and causes the one to yieldingly react against the other, thereby insuring good spring contacts between the respective folds and the co-operating flanges of the channel-shaped parting strip.

In some instances, the space between an upper and lower sash is not sufficient to permit the application of the weather strips between the same, as in the case of most hollow metal sashes, and in such case the weather strip may be applied as shown in Fig. 5. In this arrangement, the window frame is indicated by the numeral 8^a, the inside stop strip by the numeral 9^b and is located parallel and close to the adjacent face of the sash. The co-operating stop strip is bent to form an anchoring flange 18, a flat fold 19, and an inverted rectangular fold 20. The fold 19 engages and works slidably on the adjacent flange of the channel 16, while the inverted fold 20 works with frictional engagement against the interior of said channel. The anchoring flange 18 is, by screws 21 or the like, attached to the sash so that it moves vertically therewith.

The window strip illustrated in Figs. 5 and 7 is a modification of that illustrated in Figs. 1, 2 and 3, but it should be noted that one of the said strips shown in Figs. 2 and 3 may be used also in connection with the channel 16 shown in Fig. 5.

What I claim is:

35 1. The combination with a window frame and upper and lower sashes slidably mounted therein, of a parting strip in the form of a metallic channel secured to said frame between said sashes, and metallic weather strips secured to the respective sashes and formed with rectangular folds that embrace the adjacent flanges of said channel, the said folds being approximately rectangular in cross section and being formed so that the one will slide in frictional contact with the other.

2. The combination with a window frame and upper and lower sashes slidably mounted therein, of a parting strip in the form of a metallic channel secured to said frame 50 between said sashes, and metallic weather strips secured to the respective sashes and formed with folds that are approximately rectangular in cross section, the said folds having overlapped parallel portions that 55 frictionally engage the inner and outer sides of the adjacent flanges of said channel, the folds of the two weather strips being overlapped so that they slide in frictional engagement when either sash is 60 moved in respect to the other.

3. The combination with a window frame and upper and lower sashes slidably mounted therein, of a parting strip in the form of a metallic channel partly set into and 65 secured to said frame with its flanges projecting between said sashes, of metallic weather strips provided with offset flanges secured to the outer edges of the respective sashes and formed with approximately rectangular folds including parallel flat portions that embrace and frictionally engage the adjacent flanges of said channel, the said folds being overlapped and their flat inner faces being arranged for sliding engagement when the one sash is moved in respect to the other.

4. The combination with a flanged parting strip adapted to be applied to a window frame, of a weather strip adapted to 80 be applied to a sash, said weather strip being bent to form a three-ply fold having sliding frictional contact with the flange of said parting strip, that part of the fold that is remote from the anchored side of 85 the weather strip comprising two plies, the inner of which is inwardly bent and is in direct frictional contact with the flange of said parting strip.

In testimony whereof I affix my signature.

FRANK REESE.
